UNITED STATES PATENT OFFICE.

CLARENCE B. FOWLER, OF NEW YORK, N. Y.

COMPUTING DEVICE.

Application filed February 1, 1923. Serial No. 616,364.

To all whom it may concern:

Be it known that I, CLARENCE B. FOWLER, a citizen of the United States, and a resident of the city of New York, borough of Queens, 5 in the county of Queens and State of New York, have invented a new and Improved Computing Device, of which the following is a full, clear, and exact description.

This invention relates to improvements in 10 computing devices, and has particular reference to a device for determining the locality of a house number relative to streets intersecting the street on which said number is located.

15 In certain cities it is possible to determine the locality of a house number on a street by the relation of such number to the designations of two adjacent streets intersecting the first named street. More specifically, 20 the hundreds or hundreds and thousands digits of a house number on one street designate the location of said number as being between an intersecting street, the number of which is the same as said hundreds or hundreds and thousands digits, and the next succeeding intersecting street.

25 In other cities, such as New York for example, the houses on various streets and avenues are consecutively numbered from one end of a street to the other without relation to intersecting streets, thus making it virtually impossible to determine the locality of any particular house number with respect to streets which intersect the street on which 30 said number is located. Furthermore, the fact that many parallel, or substantially parallel streets and avenues are of different lengths and begin at different distances from any particular street extending transversely 35 thereof prevents the determination of the locality of a certain house number on one street when the locality of the same number on a different street is known.

An object of the present invention is to 40 provide improved means to facilitate the location of house numbers relative to streets intersecting the streets on which said numbers appear.

45 Another object is to provide a device of simple and inexpensive construction, which may be conveniently carried about the person and which may be utilized as an advertising medium, if desired.

The above and other objects will appear 50 more clearly from the following detail description, when taken in connection with

the accompanying drawings, which illustrate a preferred embodiment of the inventive idea.

In the drawings—

60 Figure 1 is a front elevation of a device constructed in accordance with the invention;

Figure 2 is a rear elevation thereof; and

Figure 3 is a transverse section on the 65 line 3—3 of Figure 1.

The invention is shown as comprising a body portion 5, preferably of rectangular formation, which may be made of any desirable material, such as aluminum, brass, 70 celluloid, or cardboard. The body portion is provided in one face thereof with a longitudinally extending groove 6, in which is adjustably mounted a slide 7 having a longitudinal slot 8 therein terminating short of 75 the ends thereof and through which extends a guide 9 which retains the slide in position and limits the movement thereof in said groove.

The body portion 5 has printed on one 80 side of the groove 6 indicia 10 designating the names of various avenues, as for example, in the city of New York. The opposite edge of the groove is calibrated and has printed thereon the figures 11 85 designating house numbers. The edge of the slide 7 adjacent the house numbers is also calibrated and contains the numbers of streets which, in the city of New York, are crosstown streets intersecting the various 90 avenues. Intermediate the ends of the slide the same is marked with an arrow 12, which is utilized in making various adjustments of the slide when determining the location of a house number of a particular avenue. 95

The utility and operation of the invention may be best explained by a concrete example. Thus, should it be desired to determine the location of the address "2046 Lexington Avenue" with respect to the crosstown street nearest said address, the slide 7 is moved in the groove until the arrow 12 is opposite the name "Lexington" on the right side of said groove, as shown in Figure 1. The house number nearest the number 100 2046 is then located in the column of figures 11 on the left side of the groove 6. Said number is 2040 and it will be found on the scale associated with the house numbers that the line designating said number 105 2040 is in registration with the line on the crosstown street number scale to which the

numeral 124 is applied. Thus, it is indicated that the number 2046 is near 124th Street on Lexington Avenue.

The opposite face of the body portion, 5 shown in Figure 2, may be provided, if desired, with a map 13 of the city illustrating the various principal streets and transit routes. Said face may also be provided with a linear scale 14 along one longitudinal 10 edge thereof.

In case the device is used as an advertising medium, the whole or a part of the face of the body portion containing the map 13 may carry an advertisement.

15 The device may also be made in circular or tubular formation if desired.

What is claimed is:

1. A new article of manufacture, including a body having indicia thereon designating the names of streets and the numbers of houses on said streets, a scale on said body associated with said numbers, a slide movable with respect to said body and having designations thereon for other streets, a 20 scale on said slide associated with said designations and with the first named scale, and means on said slide cooperating with said indicia and scales for determining the location of a given house number with respect to a certain one of said other streets.

2. A new article of manufacture, including a body having indicia thereon designat-

ing the names of streets and the numbers of houses on said streets, a scale on said body associated with said numbers, a slide 35 movable with respect to said body and having designations thereon for other streets which intersect the first named streets, a scale on said slide associated with said designations and the first named scale, and 40 means on said slide cooperating with said indicia and scales for determining the location of a given house number with respect to a certain one of said intersecting streets.

3. A new article of manufacture, including a body having indicia thereon designating the names of streets and the numbers of houses on said streets, a slide on said body having designations thereon for other 45 streets, cooperating scales in association respectively with said house numbers and designations of other streets, and means on said slide cooperating with said indicia and scales for determining the location of a street number with respect to a certain one 50 of said other streets.

4. A new article of manufacture, including fixed and movable surfaces having indicia thereon designating the names of streets and the numbers of houses, and 55 means on said surface for determining the location of a street and house number with respect to adjacent streets.

CLARENCE B. FOWLER.
